UNITED STATES PATENT OFFICE.

HARRIET LYONS REDMOND, OF BOSTON, MASSACHUSETTS, ASSIGNOR TO THE
WILLIAM CARTER COMPANY, OF NEEDHAM HEIGHTS, MASSACHUSETTS, A
CORPORATION OF MASSACHUSETTS.

BRASSIÈRE.

Application filed February 2, 1921. Serial No. 441,900.

To all whom it may concern:

Be it known that I, HARRIET LYONS REDMOND, a citizen of the United States, and a resident of Boston, in the county of Suffolk and State of Massachusetts, have invented an Improvement in Brassières, of which the following description, in connection with the accompanying drawings, is a specification, like characters on the drawings representing like parts.

This invention relates to body garments and more particularly to that type of garment known as the brassière. The object of the invention is to provide an inexpensive breast and diaphragm covering composed of light elastic material capable of providing sufficient strength to support the respective parts of the body that they are intended to cover.

20 In the accompanying drawings wherein I have shown merely for the purposes of illustration one embodiment of my invention:

Fig. 1 is a front perspective view of the garment;

25 Fig. 2 is a perspective view of the same looking from the rear; and

Fig. 3 is a detail view greatly enlarged of a section of the fabric forming the front portion of the garment.

30 In the drawings, 1 represents the brassière as a whole, the same comprising a front portion 2 including a reinforced elastic section of fabric 3 arranged to extend around the front portion of 35 the waist line for the purpose of providing support for the diaphragm. Also included in said front portion is a relatively porous elastic breast covering 4, said waist and breast covering being preferably formed of integrally knit fabric extending from side to side of the front portion of the garment while secured to opposite sides of said knit portion, preferably by stitching thereto, are sections 5 and 6 of 40 relatively inelastic, preferably woven, fabric which forms the back of the garment and are herein united near the center of the back by suitable temporary fastening means such, for example, as hooks and eyes 7 and 8.

50 The back and front portions are preferably fashioned substantially to conform to the shape of the body when the same is fastened together and means are provided such as straps 9 and 10 to extend over the

shoulders for the purpose of supporting the upper edges of the garment.

Obviously the various parts of the garment may be made of various forms and types of fabrics but herein the front portion is preferably constructed of knitted fabric 60 formed in one continuous web from top to bottom and from side to side starting preferably in a welt 11 consisting of a doubled strip of plain knitted fabric whose edges are united, during the knitting operation 65 and joined with a flat web 12 of plain fabric extending from the united edges of said welt as at 13 to the point 14, a relatively short distance below said welt.

When the knitting has progressed to the point 14 the character thereof may be and herein preferably is changed to what is known as ribbed fabric, the latter extending from the line 14 to the line 15. It is desirable that this portion of fabric should be 75 and herein it is of relatively greater elasticity than the other sections of the fabric to permit the same more readily to conform to the breast of the wearer so as to form a light, comfortable support for that portion 80 of the person without causing undue pressure to be exerted thereupon.

Hence the fabric at this point, as herein-before stated, is composed of ribbed fabric, which as is well-known is inherently more 85 elastic than plain fabric.

It is also desirable that the breast covering portions of said garment be relatively more porous than the other portions thereof to provide suitable ventilation, thus rendering the garment cooler and more sanitary 90 than would otherwise be the case.

One method of producing fabric comprising said breast covering portion so as to render the same porous is to produce the 95 same on the well known "Cotton" knitting machine wherein certain loops are transferred, during the knitting operation, to provide openings at certain definite intervals in the wales of the fabric.

100 Adjoining the porous elastic breast covering portion 4 of said garment, commencing at the line 15, I preferably form integral with and as a continuation of said section 4 a narrow strip of plain knitted fabric 16 105 extending to the line 17 and here I preferably again change the character of the knitting from plain to ribbed fabric and, dur-

ing the knitting thereof, effect the insertion 5 of elastic bands 18, 18 between the wales in opposite faces of said fabric, thus producing the reenforced elastic fabric 3 which tends across the front portion of the waist line and provides yielding support for the diaphragm. Through the terminal loops of the ribbed fabric composing the section 3 is inserted one of said elastic bands which constitutes the lower edge of said reenforced elastic band and prevents ravelling of the loops of said fabric.

It is often desirable that the upper welted edge of the front portion of said garment 15 be drawn more tightly to fit the bust and, therefore, a suitable puckering string or, as herein shown, an elastic strip 19 is inserted throughout the length of said welt and is 20 stitched, together with the opposite edges of the fabric constituting the front portion of the garment, to the edges of the relatively inelastic fabric composing the back of the garment, the tension of said strip 19 being predetermined to cause the garment to fit 25 snugly.

By forming the front portion of the garment as hereinbefore described from knitted fabric, the operations necessary to produce the same will be greatly reduced in number 30 with the result that a more economical and durable garment will be produced and at the same time one which will fit snugly at all portions without causing discomfort to the wearer.

35 Furthermore in view of the fact that knitted fabric is used for the front section of the garment it will be obvious, owing to the inherent elasticity thereof that the garment will be capable of conforming to a large 40 variety of forms and therefore need not be made in exact sizes.

So far as I am aware I am the first to combine in a single garment both the features that are served by the garment herein disclosed, namely, the relatively free support 45 of the bust portions and the firmer and more binding support of the diaphragm.

Having thus described one illustrative embodiment of my invention, I desire it to be understood that although specific terms are employed, they are used in a generic and descriptive sense and not for purposes of limitation, the scope of the invention being set forth in the following claims.

Claims:

1. A brassière comprising in combination a front portion 2 knitted as one continuous web from top to bottom and from side to side and including a strip of plain knit fabric 12 having a welt 11 along its upper edge 60 enclosing an elastic puckering member 19, a ribbed knit breast covering 4 porous relative to said strip of plain knit fabric 12, and a ribbed knit diaphragm covering 3 reinforced by elastic strands and integrally 65 united to said breast covering 4 by an intermediate strip of plain knit fabric 16, and a substantially inelastic two-part back portion 5, 6 secured to opposite sides of said front portion.

2. A brassière comprising a wholly knitted front portion formed as a continuous web from top to bottom and from side to side, and a substantially inelastic back portion connected to the lateral edges of the front portion, said front part having at its upper portion a ribbed knitted structure of relatively greater elasticity and relatively more porous than the other parts of the fabric to constitute a breast covering and containing transferred loops providing the openings at definite or predetermined intervals, said breast covering having at its upper edge a transverse portion having a greater tension than said breast covering portion, and having extending from its lower edge a knitted portion constituting a diaphragm support and in which elastic bands are inserted in the knitted wales to provide a yielding support for the diaphragm.

In testimony whereof, I have signed my name to this specification.

HARRIET LYONS REDMOND.
